UNITED STATES PATENT OFFICE

SAMUEL HERLICH, OF PHILADELPHIA, PENNSYLVANIA

BATHING SUIT

Application filed October 30, 1928. Serial No. 315,941.

My invention relates to bathing suits and particularly to the one-piece type of suit.

One-piece bathing suits are customarily made of knitted fabric with the wales of the goods running longitudinally of the suit, that is, the suit is stretchable transversely but resists any tendency to stretch it longitudinally. Unless the suit is carefully fitted, it will either bind when the wearer bends or will lack the neat, snugly fitted appearance demanded by bathers today. Consequently, a person cannot comfortably wear a suit which fits another person of the same chest measure but of lesser height. One-piece bathing suits are generally entered through the neck of the suit and one or both of the shoulder straps are separable to facilitate donning the garment. The ends of a separable strap are connected by a button and button-hole or other fastening means which will often become unservicable after the suit has been in use for a time and the ends often become disconnected while the suit is being worn.

The object of this invention is to provide a one-piece bathing suit that will comfortably and neatly fit persons differing in girth and stature, which will yield to the movements of the body, and in which separable shoulder straps are unnecessary.

The invention consists in providing a suit having the rear piece of the trunks stretchable longitudinally of the suit and bifurcated to receive a crotch piece which is stretchable transversely, the balance of the suit being stretchable transversely and provided with shoulder straps which may be non-separable, as illustrated by the embodiment shown in the accompanying drawings, in which

Figure 1 is a front view of a suit constructed according to my invention, showing it folded flat and with the skirt broken away to expose the trunks.

Figure 2 an enlarged longitudinal section, taken in the plane of line 2-2 on Figure 1 but showing the skirt intact and the suit somewhat distended,

Figure 3 a bottom view, as indicated by line 3-3 on Figure 2, but drawn to a larger scale and showing the suit further distended,

Figure 4 a rear view of the suit shown in Figure 1, showing same folded flat and with the skirt broken away to expose the trunks, and

Figures 5 and 6 views of the front and rear pieces of the trunks as they appear before being incorporated in the suit.

Referring more in detail to the drawings, the suit has a body part consisting of a shirt 10, an integral skirt 11, and shoulder straps 12 which need not be separable; the wales of the goods running longitudinally in the customary manner. A pair of trunks, secured to the body part approximately at the waist line by stitches 13, consists of a front piece 14 and a rear piece 15.

The rear piece has the wales of the goods running transversely and is provided with a bifurcation 16 (see Figure 6) which may extend more than a third of the distance from the center of the crotch to the waist line. The front piece has the wales of the goods running longitudinally and is provided with an extension 17 which is preferably formed integral with the front piece and of substantial width so as to provide ample room and elasticity in the crotch of the garment.

The front piece, which is preferably wider than the rear piece, has its side edges 18 and 19 secured to the side edges 20 and 21 of the rear piece to form seams 22 and 23, respectively, and the edges of extension 17 are secured to the edges of bifurcation 16 to form seam 24. When the suit is folded flat, seams 22 and 23 will appear on the back of the trunks and the greater part of seam 24 be concealed as the rear piece will fold along lines 25 and 26.

When a person bends over, the distance from the crotch to the top of the shoulders increases along the back and causes a conventional bathing suit to bind as it has little elasticity longitudinally. When my improved suit is worn, however, the wearer can bend and move with perfect freedom due to the seat of the trunks being stretchable longitudinally of the garment and extension 17 being stretchable transversely. Further, the suit will fit persons of different stature and may be donned without separating one or

both of the shoulder straps as the rear piece of the trunks will give sufficiently to allow non-separable straps to be slipped over the shoulders.

Various changes in details of construction may be made in the garment within the scope of the invention without departing from the spirit of the invention as hereinbefore set forth and hereinafter claimed.

19 I claim:

15 1. A bathing suit of knitted material comprising a body part and a pair of trunks secured to the body part and consisting of a rear piece, having the wales of the material running transversely of the suit and being bifurcated for more than one-third of the distance from the center of the crotch to the top of the trunks, and a front piece, of greater width than the rear piece, secured to the rear piece and having the wales of the material running longitudinally and being provided with an integral extension which is secured in the bifurcation in the rear piece and forms the crotch of the garment.

25 2. A bathing suit composed of knitted fabric and comprising a nether portion, the posterior part of which has its wales extending transversely, and the wales slitted for a distance from the bottom upwardly, and an attached anterior part, having wales extending vertically with a central extension, said central extension having its edges secured to the edges of the slit.

30 In testimony I have signed my name to this specification.

SAMUEL HERLICH.
